[57] CLAIM

The ornamental design for a computer enclosure, as shown and described.

DESCRIPTION

FIG. 1 is a front, top right side perspective view of a computer enclosure showing our new design;

FIG. 2 is a rear, bottom, left side perspective view of FIG. 1;

FIG. 3 is a front elevational view of FIG. 1;

FIG. 4 is a front elevational view of a second embodiment of the computer enclosure of FIG. 1;

FIG. 5 is a right side elevational view of FIG. 1;

FIG. 6 is a rear elevational view of FIG. 1;

FIG. 7 is a rear elevational view of the second embodiment of the computer enclosure of FIG. 1;

FIG. 8 is a left side elevational view of FIG. 1;

FIG. 9 is a top plan view of FIG. 1; and,

FIG. 10 is a bottom plan view of FIG. 1.

The undisclosed views of the second embodiment are identical to those of the first embodiment.
